UNITED STATES PATENT OFFICE.

MANUEL W. KAHLE, OF DUKE CENTRE, PENNSYLVANIA, ASSIGNOR TO
MARTHA JANE KAHLE, OF SAME PLACE.

CALIPERS AND CENTERING DEVICE.

SPECIFICATION forming part of Letters Patent No. 230,421, dated July 27, 1880.

Application filed June 3, 1880. (No model.)

To all whom it may concern:

Be it known that I, MANUEL W. KAHLE, of Duke Centre, in the county of McKean and State of Pennsylvania, have invented certain 5 new and useful Improvements on a Centering Device; and I do hereby declare that the following description of my said invention, taken in connection with the accompanying sheet of drawings, forms a full, clear, and exact specification, which will enable others skilled in the art to which it appertains to make and use the same.

This invention has general reference to a centering device; and it consists, essentially, 15 in the peculiar construction of parts and combination of elements, as hereinafter first fully set forth and described, and then pointed out in the claim.

In the drawings already referred to, which 20 serve to illustrate my said invention more fully, Figure 1 is a front elevation of my improved centering device. Fig. 2 is a similar view of a portion thereof, illustrating its application. Fig. 3 is a plan, and Fig. 4 a plan 25 of the central tube.

Like parts are designated by corresponding letters of reference in all the figures.

The object of my present invention is the 30 production of a convenient instrument for finding the center of cylindrical or other work, the center of cylinders or other hollow parts, my said invention being an improvement upon a similar device described and claimed in a specification filed by me in the United States Patent Office May 17, 1880, as serial No. 9,934. 35 In this device I employ one pair of legs pivoted to a central tube, through which is passed a scribing-rod, the legs being connected to a pinion, so as to move equally from or toward said central scribe. This device is particularly designed for finding the center line 40 of angular parallel bodies, while my present instrument is more particularly adapted for finding the center of cylinders, cylindrical bodies, &c.

In the drawings, the letter A designates a 45 tubular body having near its lower end four pairs of lugs, B, between which are pivoted four curved legs, C, the upper ends of which 50 are formed into segments D D D' D', having

their centers in the points of pivoting of said legs C.

The segments D' D' of two oppositely-located legs are of less diameter than those at right angles, (marked D,) so as to allow them 55 to pass below the said segments D' D'. The faces of these segments are provided with teeth engaging a bevel-pinion, E, revolving on the end of the tube A, the same as that described in the specification already referred to.

It will now be readily observed that by revolving the said pinion by its head F the legs C are moved in a direction corresponding to that of said pinion, and that to find the center of a circular cylinder—G, for instance—nothing needs to be done but to grasp the body by the four legs C, as shown in Fig. 2, and then to slide the scribe H down upon the body, when said scribe will correctly indicate the center of said body.

It will be further observed that it makes no difference whether the part of which the center is desired to be found is above or below the plane where the points of the legs C embrace said body, so that the center of raised 75 or depressed surfaces may be as readily found and marked as those on the same plane.

In finding the end centers of shafting or the centers of cylinders, holes, or other deep places where easy access with other tools cannot be 80 had, this device is as readily adjusted and a convenient means for accomplishing the desired result as any that can be devised, while, owing to its extreme portability and cheapness, it is far superior to any other self-centering device with which I am acquainted.

It is perfectly obvious that the points of the legs C may be formed into the usual shape of compasses, inside calipers, or both inside and outside calipers, without changing the nature 90 of my invention.

I do not wish to be understood as here claiming a center-scriber having two legs with a central scribe between them, such a device being fully described and claimed in my said application of May 17, 1880; but,

Having thus fully described my invention, I claim as new and desire to secure to me by Letters Patent of the United States—

A centering device consisting, essentially, of 100

a tubular body, A, having near its lower end lugs, within which are pivoted two pairs of legs, C, having on their upper ends segments D D D' D', engaging a pinion, E, the segments D' D' being of less diameter than the segments D D, so as to pass underneath them at right angles to the line of movement of said segments D D, substantially in the manner as and for the object specified.

In testimony that I claim the foregoing as my invention I have hereto set my hand in the presence of two subscribing witnesses.

MANUEL W. KAHLE.

Attest:

MICHAEL J. STARK,
GEORGE H. THOMPSON.
